UNITED STATES PATENT OFFICE.

ZACHRIAH T. BUSH, OF STANTON, MICHIGAN.

ROAD-CART.

SPECIFICATION forming part of Letters Patent No. 378,354, dated February 21, 1888.

Application filed October 28, 1887. Serial No. 253,651. (No model.)

To all whom it may concern:

Be it known that I, ZACHRIAH T. BUSH, a citizen of the United States, residing at Stanton, county of Montcalm, State of Michigan, have invented certain new and useful Improvements in Road-Carts; and I declare the following to be a full, clear, and exact description of the invention, such as will enable others skilled in the art to which it appertains to make and use the same, reference being had to the accompanying drawings, which form a part of this specification.

My invention relates to improvements in road-carts; and it consists of the combinations of devices and appliances, hereinafter specified, and more particularly pointed out in the claims.

The objects of my invention are, first, to provide improved adjusting mechanism whereby the supporting-spring may be adjusted according to the amount of load carried by the cart; second, to provide an improved arrangement of the spring and hangers, such that the spring is left free at its middle, being supported at its ends, and the load being applied between the middle portion and the ends; third, to provide improved seat-bar hangers whereby the spring is permitted to swing backward or forward as the mechanism is adjusted to regulate the spring for lighter or heavier loads, thereby keeping the spring in a plane at right angles to the direction of the pressure exerted by the load; fourth, to provide improved seat-bars of such construction as to be out of the rider's way in climbing into and out of the cart, said seat-bars being bent down to form the frame of the box.

In the drawings, Figure 1 is a side elevation of a road-cart embodying my invention, with one wheel removed. Fig. 2 is a vertical cross-section on line $\alpha\alpha$, Fig. 1. Fig. 3 is an enlarged detail of the seat-bar hanger.

A represents the axle, and B the thills, of my improved road-cart; C, the seat-bars, and F the supporting-spring.

The seat-bars C are pivotally connected to the draft-bar E, as shown at e, and are bent downwardly and then rearwardly, so as to form the frame for the box of the cart, and then upwardly to support the seat. Upon the under side of the seat-bars C, I provide hanger-brack-

ets c, within which the spring F is movably engaged with the seat-bar hangers f. These seat-bar hangers f are engaged upon the brackets c in any convenient manner, as by means of a staple, c'. Hangers f are also provided with anti-friction rollers f', having bearings upon the upper side of the spring.

Upon the under side of the thills B, I provide brackets b, said brackets provided with a series of notches, d d' d'', for the engagement of the suspending loops or bails b'. These loops are secured to the ends of the spring F in any suitable manner—as, for instance, by means of a bolt, b''.

The operation of my device is as follows: When it is desired to increase the weight of the load—as, for instance, carrying two passengers instead of one—the seat is raised, so as to relieve the weight upon the loops b', and said loops are adjusted forward and engaged in the notch d'', thus elevating the seat-bars and seat, when the additional weight will not depress the seat beyond the horizontal position. When it is only desired to carry a light load, the loops are released and then engaged in the notch d, thus allowing the seat-bars and seat to occupy a position somewhat lower, so that when a light load is carried the spring will be depressed to a horizontal position. Thus it will be seen that the spring may be quickly adjusted to bear a heavy or a light load, and to support the seat in the same position when carrying two persons as when carrying one. The spring, being left free at its middle, is permitted to yield at this portion, thus increasing the elasticity of the spring. The adjustable connection of the seat-bar hangers f with the brackets c permits the spring to be inclined forward or backward, according to the position occupied by the loops b', thus keeping the plane of the spring at right angles to the direction of the pressure of the load.

This brings the strain squarely upon the spring in the proper direction and without any twist upon the spring or the hangers. The seat-bars being bent down, as shown, to form the frame of the bottom of the cart, places said seat-bars out of the way, so that in getting into or out of the cart the rider has nothing to climb over, as in carts of ordinary construction. This is a very desirable feature, as a great deal of an-

noyance is caused by the necessity of climbing over the seat-bars in entering or leaving the ordinary styles of road-carts. I would have it understood, however, that I do not desire to limit myself to the exact construction shown, as I might employ various modifications in the arrangement of the spring and the supporting loops or bails, and also in the construction and arrangement of the seat-bars and seat-bar hangers, without departing from the principle of my invention.

Having described my invention, what I claim is—

1. In a road-cart, a spring adjustably supported at its ends and free at its middle portion, and having bearings for the frame of the box between its ends and its middle portion, substantially as described.

2. In a road-cart, a spring adjustably suspended at its ends from the thills and being free at its middle portion, and in connection therewith seat-bars bent to form the frame of the box and having bearings between the ends and the middle portion of the spring, through which said spring is movable longitudinally, substantially as described.

3. In a road-cart, a spring adjustably suspended at its ends from the thills and left free at its middle portion, and having anti-friction bearings for the frame between its ends and middle, and in connection therewith means,

as set forth, for adjusting the spring for heavy or light loads, substantially as described.

4. In a road-cart, seat-bars bent to form the frame of the box and provided with hangers for engaging the spring, substantially as described.

5. In a road-cart, seat-bars pivotally connected to the draft-bar and bent to form the frame of the box, said seat-bars provided with brackets and adjustable hangers to engage the spring, substantially as described.

6. In a road-cart, the spring adjustably connected at its ends to the thills and free at its center, and seat-bars pivotally connected to the draft-bar, said seat-bars being bent to form the frame for the box and being provided with brackets and adjustable hangers to engage the spring, substantially as described.

7. In a road-cart, the spring adjustably suspended at its ends from the thills by means of loops or bails, and in connection therewith notched brackets, said loops or bails adapted to be adjustably engaged upon the notched bracket, substantially as described.

In testimony whereof I sign this specification in the presence of two witnesses.

ZACHRIAH T. BUSH.
